UNITED STATES PATENT OFFICE.

BESSIE E. DANIEL, OF KURTZ, INDIANA.

BUZZ-BALL.

1,076,354.

Specification of Letters Patent. Patented Oct. 21, 1913.

Application filed November 20, 1912. Serial No. 732,604.

To all whom it may concern:

Be it known that I, BESSIE E. DANIEL, a citizen of the United States, residing at Kurtz, in the county of Jackson and State 5 of Indiana, have invented certain new and useful Improvements in Buzz-Balls, of which the following is a specification.

This invention relates to certain new and useful improvements in whirling toys, and 10 has for its primary object the provision of a toy of this nature which shall be extremely simple in its construction, attractive to the eye and very musical.

Another and more specific object of the 15 invention resides in the provision of a toy of this nature consisting of a hollow spherical body formed with diametrically opposed openings therein and having a centrally positioned disk apertured to receive a cord 20 which passes through the first mentioned openings.

The invention also aims to generally improve toys of this nature, to render them 25 more attractive, durable and commercially desirable.

With these and other objects in view, as will become more apparent as the description proceeds, the invention consists in certain novel features of construction, combination and arrangement of parts as will 30 be hereinafter fully described and claimed.

For a complete understanding of my invention, reference is to be had to the following description and accompanying drawings, in which,

Figure 1 is a side elevation of my improved toy, Fig. 2 a sectional view through the same on the plane of line 2—2, parts thereof being shown in elevation, and Fig. 40 3 is a sectional view taken at right angles to the plane of Fig. 2.

Referring to the drawing by numerals, 1 designates a hollow sphere preferably formed of some light material, such as pasteboard, and having the diametrically positioned openings 2. A disk 3 is centrally positioned within the sphere 1 and has formed upon its diametrical center the openings 4, through which a looped string 5 passes, said string also passing through the openings 2. A plurality of bells 6 are attached to the sphere 1 by means of the wire 7. This wire is prevented from slipping off the sphere 1 by a strip 8 of flexible material such as cloth or paper. This strip

and also the strips 9 may be variously colored so as to add to the attractiveness of the toy. To further increase the musicalness of the toy, I provide a plurality of sounding reeds 10, which are fixed at their 60 outer ends within openings in the sphere 1, and which may be so constructed as to produce different musical notes as air is drawn through them.

In the operation of my improved toy the 65 string is first twisted a few times and then by moving the outer portions thereof alternately toward and away from each other the sphere is caused to rotate rapidly, first in one direction and then in the other. As 70 the sphere rotates air will be drawn through the openings over the reeds 10 producing a musical sound, and at each reverse movement the bells 6 will ring. It will be seen that the disk 3 reinforces the sphere and 75 that the spaced openings 4 in said disk serve to spread the strands of the string 5, whereby the sphere may be easily rotated. The wire 7 provides an easy method of attaching the bells, and the ornamental strips 8 80 and 9 serve the double purpose of securing the wire 7 in position and increasing the attractiveness of the toy.

It is to be understood that while I have shown and described a preferred embodiment of my invention, I do not wish to be limited to this exact construction, but may make such changes as will fall within the scope and spirit of the invention.

I claim:

A whirling toy comprising a hollow sphere, having diametrically opposed openings formed in the wall thereof, a centrally positioned disk mounted within said sphere and formed with a pair of spaced openings, 95 a looped string, having each of its strands passed through the openings in the sphere, and one of its strands passed through each of the openings in said disk, a wire extending circumferentially around the periphery 100 of the sphere, a plurality of bells secured to said wire, and a plurality of sounding reeds having their outer ends fixed in openings in the walls of the sphere.

In testimony whereof I affix my signature in presence of two witnesses.

BESSIE E. DANIEL.

Witnesses:

CLYDE DANIEL,
LULA M. SUMMA.
